UNITED STATES PATENT OFFICE.

JAMES HOLT AND ANNIE HOLT, OF MELBOURNE, VICTORIA.

METAL TROUSERS-BUTTON.

SPECIFICATION forming part of Letters Patent No. 685,208, dated October 22, 1901.

Application filed June 22, 1900. Renewed July 31, 1901. Serial No. 70,411. (No model.)

To all whom it may concern:

Be it known that we, JAMES HOLT and ANNIE HOLT, subjects of Her Britannic Majesty Queen Victoria, residing at 422 Queen street, 5 Melbourne, in the county of Bourke and Colony of Victoria, have invented a new and useful Metal Trouser-Button, of which the following is a specification.

Our invention relates to an improvement in metal trousers-buttons, in which three sharp prongs are pierced from the center bowl of the button. These prongs are cut on two sides only and bent down to a right angle at their base. These buttons can be expeditiously and firmly fastened to the garment by pressing the prongs through the cloth and a small leather washer placed at the back of the cloth and then setting down the prongs on the reverse side with a suitable concave 20 tool.

The object of our invention is to provide a trousers-button that can be fastened to the garment with metal prongs instead of the ordinary sewed-on button at present in use.

25 In the accompanying sheet of drawings the large or suspender button is shown full size, the small or fly button is not shown, it being exactly the same as the large one in every particular, but proportionally smaller.

30 Similar letters refer to similar parts throughout the several views.

Figure 1 is a front view of a suspender-button ready to use. Fig. 2 is a front view before the prongs are bent out after cutting them. Fig. 3 is a sectional view on the line CD of Fig. 1. Fig. 4 is a sectional view on the line EF of Fig. 1. Fig. 5 is a sectional view on the line AB of Fig. 1, drawn horizontally. Fig. 6 is an edge view showing the prongs pressed through the cloth and the leather washer and showing in sectional view a concave tool and cloth. Fig. 7 is a sectional view on the line AB of Fig. 1, showing also the cloth in section with the button secured thereto. 40 Fig. 8 is a back view of the button fastened to the cloth, showing the prongs. Fig. 9 is a front view of the button fastened to the cloth.

Our button before the prongs are punched 45 from the center bowl resembles the ordinary trousers-button in size and section, except

that it is deeper and wider in the center bowl. (See Figs. 1 and 5.)

The blanks for our buttons are cut and stamped to the required shape in the usual 55 way. The single prong b', Fig. 2, is then cut on two sides only and bent down to a right angle at its base, as shown at b', Fig. 3, by the back of the punch as it passes through the cutting-die. The small piece c, Fig. 2, is 60 then pierced out to separate the prongs b b at their base, as shown at Figs. 2 and 4. The prongs b b, Fig. 2, are then cut and bent to a right angle, as shown in Fig. 4, in the same manner as single prong b'. The three prongs 65 b' and b b having been cut and bent from the center bowl on the zigzag line a', Fig. 2, leaves the open space a, Figs. 1 and 9, in the center of the bowl of substantially the shape of a keystone. 70

Our buttons are fastened to the garments in the following manner: The three prongs b' and b b, Fig. 6, are pressed through the cloth d and through the leather washer e. The prongs b' and b b are then set down, as 75 shown in Figs. 7 and 8, with a concave tool f, Fig. 6. This embeds the points of the prongs b' and b b, Fig. 7, in the leather washer e and depresses the leather washer e in the center, forcing the cloth d into the aperture 80 a. The cloth being caught in this manner fastens the buttons firmly to the garment. When the leather washer e, Fig. 7, is depressed in the center, it curls up at the edge around the prongs b' and b b (see Figs. 7 and 85 8) and prevents them from scratching the body or tearing the linings or underwear or from cutting through the cloth to the front.

Having fully described in detail the nature of our invention and how our trousers-buttons are to be made and fastened to the garment, what we claim as our invention, and wish to secure by Letters Patent, is—

1. A trousers-button consisting of a circular metal plate or disk having a concentric cup 95 stamped therein in the flat bottom of which is an opening of substantially keystone shape, the material displaced to form said opening in the form of three triangular prongs remaining attached by their bases to the metal 100 of said bottom and projected rearward therefrom, two prongs at one edge of the opening

and the third at the opposite edge between the first-named two, substantially as set forth.

2. The combination with a trousers-button consisting of a circular metal plate or disk 5 having a concentric cup stamped therein in the flat bottom of which is an opening of substantially keystone shape, the material displaced to form said opening in the form of three triangular prongs remaining attached 10 by their bases to the metal of said bottom and projected rearward one from one edge and two from the opposite edge of said opening, of a piece of cloth pierced by said prongs

and a leather washer on the cloth pierced by said prongs, the leather washer and cloth 15 being pressed inward in cup shape into the opening and the points of the prongs being twisted back and embedded in the leather washer, substantially as set forth.

Dated the 17th day of February, 1900.

JAMES HOLT.
ANNIE HOLT.
